UNITED STATES PATENT OFFICE.

RUFUS S. MERRILL, OF BOSTON, MASSACHUSETTS, ASSIGNOR TO THE ACME PAPER BOX COMPANY, OF SAME PLACE.

FOLDING BOX.

SPECIFICATION forming part of Letters Patent No. 326,577, dated September 22, 1885.
Application filed February 6, 1885. (No model.)

To all whom it may concern:

Be it known that I, RUFUS S. MERRILL, of Boston, in the State of Massachusetts, have invented a certain new and useful Improvement in Folding Boxes, of which the following is a specification.

The folding box in which my improvement is comprised has sides which fold flat upon one another, and hinged flaps which close the ends of the box. I make these end flaps with hinged extensions, which, when the flaps are folded to place, fold down upon one and the same side of the box, and are of such length that they preferably meet and overlap one another. The box-body itself is virtually a compound box or an assemblage of boxes, all of which together form the body of the box, and are so constructed and arranged that the latter can fold flat without disturbing the relations of its component parts. The box is intended for the packing and transporting of bottles and the like, which must be kept separate from and out of contact with one another to prevent breakage.

25 In the accompanying drawings is represented the preferred embodiment of my invention, the box there represented being virtually two boxes in one.

Figure 1 represents the box in perspective 30 in set-up form with the end flaps folded and closed. Fig. 2 is a cross-section on line 2 2, Fig. 1. Fig. 3 is a view of the box in knock-down or flattened condition. Fig. 4 is a section on line 4 4, Fig. 3.

35 The compound box or package represented is one intended to hold two liquor-flasks. To this end it should consist, virtually, of two distinct boxes or compartments, which, while adapted to fold and unfold as one, will nevertheless hold the article contained in the one separate from and out of contact with the other. The preferred way of accomplishing this result is indicated in the drawings.

45 One side of the box-body is formed by a strip, A, having the hinged flaps *a* and hinged extensions *b*, formed, preferably, by making the strip of a proper length and then scoring or creasing it along the proper lines of fold of the flaps and extensions. The other three sides,

B C D, of the body are formed of a continuous strip creased along the proper lines for the folding of the sides, and provided at each edge with a flap, *c*, which is pasted or otherwise secured to the inner face of strip A. I thus obtain the four outer walls and the two end flaps, &c., of the compound box.

The division of this compound box into two separate compartments is effected in this instance by a longitudinal partition-strip, E, extending between and attached permanently to two opposite sides—in this instance the sides A C—and parallel with and equidistant from the other two sides, B D. This partition-strip is hinged to sides A C, so that it will fold and unfold with the remaining parts of the folding box-body. For this purpose it is attached to the sides A C by tongues *d*, formed by creasing or scoring at proper points the strip from which the partition is made, the hinges of the partition thus being at the creases or scores between it and the tongues.

In this way I obtain a compound box made up of a number of distinct boxes or compartments which fold and unfold as one. It is shown in flattened condition in Figs. 3 and 4. 75

When the box is unfolded and closed, the extensions *b*, by overlapping one another, are brought to a position where they are readily secured and held in place by the cord *e*, used to tie up the box. This arrangement serves 80 to materially strengthen the box as well as to stiffen it.

Having described my improvement and the best way now known to me of carrying it into effect, what I claim, and desire to secure by 85 Letters Patent, is—

A compound folding box having a body composed of the strip A, having hinged end flaps, *a* *b*, and the creased strip B C D, in combination with the hinged partition E, substantially as and for the purposes hereinbefore set forth.

In testimony whereof I have hereunto set my hand this 26th day of January, 1885.

RUFUS S. MERRILL.
